UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,568, dated August 21, 1894.

Application filed July 28, 1894. Serial No. 518,885. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental wreaths with torch-like ornaments in the 10 center and small rosettes or flower shaped ornaments arranged between the wreath ornaments as represented in the accompanying drawing. The border or upper portion of the 15 design is formed of lyre-shaped ornaments connected by ornamental wreaths with torch-

like ornaments in the center, and is separated from the hanging or body of the design by an ornamental band containing a row of small rosettes or flower shaped ornaments as shown.

What I claim is—

1. The design for wall paper herein shown and described.

2. In the design for wall paper, the border herein shown and described.

Witness my hand this 26th day of July, 25 1894.

CHARLES BOOZE.
